UNITED STATES PATENT OFFICE.

JOSEPH WARREN HORTON, OF EAST ORANGE, NEW JERSEY, ASSIGNEE TO WESTERN ELECTRIC COMPANY, INCORPORATED, OF NEW YORK, N. Y., A CORPORATION OF NEW YORK.

METHOD OF AND MEANS FOR TRANSMITTING SIGNALS.

Application filed December 13, 1920. Serial No. 430,143.

This invention relates to a carrier current system and more particularly to an arrangement whereby the amplitudes of the carrier and side-band current components supplied to the line by a modulating tube may be regulated.

In a system using a carrier current of frequency within the voice range modulated by a current of the usual ringing frequency, the amplitude of the carrier current in the modulator output circuit will exceed that of the side-bands. If the output current of a modulator is impressed upon a resonant circuit tuned to the frequency of one of the side-bands, the impedances offered to the carrier current would be greater than that offered to the selected side-band and the amplitude of the current of side-band frequency would exceed that of the carrier.

In such a system, wherein a signal is transmitted through voice range repeaters, the line current capable of developing a fixed amount of energy of the original frequency when demodulated in any given circuit will be a minimum when the side-band and carrier current components are of equal amplitude, hence it will be obvious that under either of the conditions stated above, the maximum signaling effect will not be obtained at the distant receiving station.

The primary object of this invention is to provide an arrangement in a system of this type whereby a maximum signaling current may be transmitted to the receiving station under the above-mentioned conditions for line current and power.

Another object is to control the ratio of the amplitudes of the carrier and side-band current components supplied by the output circuit of a modulating tube.

A further object is to equalize the amplitudes of the carrier and side-band current components transmitted to the line.

These objects and others which will appear as the nature of the invention as set forth may be accomplished by associating with the output circuit of a modulating tube, a resonant circuit having means to vary its relative impedance to the current components of carrier and side-band frequencies.

The ratio of these impedances depends upon the frequency relation of the two currents and the resonant characteristics of the circuit, hence with given frequencies for

these currents, the impedances offered to the two frequencies in question may be made inversely proportional to their amplitudes, by varying the damping of the resonant circuit.

In the arrangement herein shown an adjustable resistance is connected in a tuned circuit associated with the modulator output circuit for this purpose, and by a proper adjustment of this resistance, equalization of the amplitudes of the current components of carrier and side-band frequencies, under the conditions hereinbefore mentioned as to power and line current, may be secured.

For a complete understanding of the invention reference will now be made to the following specification and attached drawing in which, Fig. 1 shows one form of the invention and Fig. 2 an alternative method for connecting the output circuit of the modulator to the input circuit of the amplifier in an arrangement of the type shown in Fig. 1.

One means for supplying a carrier current is herein shown as consisting of a vacuum tube oscillator, though any other form of generator adapted to supply a current of carrier frequency may be used.

As is well known an oscillator of this type comprises a hot filament or cathode, a grid or impedance control element 2, and an anode or plate 3, enclosed in an evacuated vessel 4, having an input circuit connected between the filament and grid, and an output circuit including the filament and a plate; a coupling connecting these two circuits so that increments of energy are derived from the output circuit and fed back to the input circuit to control the flow of current in the former circuit, and an oscillatory circuit associated with the feed-back connector to determine and control the frequency of the oscillations produced by the generator.

As herein illustrated, the input circuit may be traced from the filament 1, through the winding 5 shunted by an adjustable condenser 7 and the battery 8 to the grid 2. The output circuit includes the filament 1, plate 3, condenser 9, coil 6, and a resistance 11. The condenser 9 serves as a low impedance path for the high frequency oscillations produced in the output circuit, while preventing direct current flow thereto from

the source of plate current. A choke coil 10 connected in the plate supply circuit prevents the flow of oscillatory current through the plate current source, while permitting uni-directional current to flow from said source through the plate circuit. In this case the coils 5 and 6 are inductively related to constitute the feed-back coupling and the coil 5 with the associated condenser 7 constitutes a tuned circuit, the natural period of which may be varied to control the frequency of the oscillations supplied by the plate circuit which, as stated above, includes the resistance 11.

15 This resistance operates as a potentiometer and by adjusting the sliding contact 12 associated therewith, the carrier voltage supplied to the input circuit of the modulating tube 16 may be regulated. The 20 modulating tube comprises a filament 13, grid 14, and a plate 15 enclosed in a vacuum tube 16 having an input circuit extending from the filament 13 to the grid 14, which includes a portion of the resistance 11 determined by the position of the contact 12, a tuned circuit consisting of an inductance 17 shunted by an adjustable condenser 18 and a polarizing battery 19 for the grid 14.

A source of signaling current, herein 30 conventionally indicated as a vibratory current source 20, but which would preferably be the usual plant supply, is connected to a winding 21 which is inductively associated with the coil 17 to supply alternating current of the usual ringing frequency to the input circuit of the modulating tube. The 35 tuned circuit 17-18 is resonant to the ringing frequency.

The output circuit of the modulator 40 includes filament 13, plate 15, a condenser 21, and a tuned circuit comprising an inductance 22 shunted by an adjustable condenser 23. This circuit is tuned to the side-band selected for transmission, but such tuning should be sufficiently broad to permit the flow 45 of some current of carrier frequency while suppressing the other side-band. Under these conditions owing to the large amplitude of the carrier current component relatively to that of the selected side-band frequency, the amplitude of the current component of carrier frequency present in this circuit will exceed that of the side-band to be transmitted.

55 The condenser 21 operates to exclude uni-directional space current from the oscillatory circuit 22-23, while permitting the flow of high frequency current thereto. A choke coil 24' serves as a low impedance path for direct current supplied by the source of plate potential, to be referred to more specifically later, while confining the oscillatory current to the plate circuit of the modulator.

60 Inductively related to the inductance 22 is

a winding 24 consisting of a few turns which is included in a resonant circuit tuned to the selected side band. In addition to the winding 24, the resonant circuit includes an inductance 25, a resistance 27, and an adjustable condenser 26 connected in shunt to the winding 24, inductance 25 and resistance 27.

70 Modulated current is transmitted to the resonant circuit by the coupling connection between the windings 22 and 24. The resistance 27 is provided with a sliding contact 28 whereby the amount of the resistance included in the resonant circuit may be regulated.

75 The frequency relation of the carrier and signaling currents being fixed, the ratio of the impedances offered to the current components of carrier and side-band frequencies flowing through the last-mentioned tuned circuit will depend upon the resonant characteristics of said circuit. By varying the position of the sliding contact 28, the amount of the resistance 27 included in this circuit may be regulated, hence the relative impedances offered to currents of these two 80 frequencies may be made inversely proportional to the impressed amplitudes.

85 It will therefore be evident that by adjusting the contact 28 to include a proper amount of the resistance 27, the amplitudes 90 of the current components of the two frequencies in question may be made equal.

95 Should amplification of the current components to be supplied to the transmission circuit be desirable, the resonant circuit 24-100 25-26-27 will be included in the input circuit of an amplifier 32, which extends from the filament 28' to the grid 30. A polarizing battery 29 for the grid 30 may be connected in the input circuit of the amplifier.

105 The alternating current output circuit of the amplifier, which includes the filament 28', plate 31, and the condenser 33 is connected to the toll line L which includes voice range repeaters VR. The condenser 33 constitutes a low impedance path for the amplified current, but imposes an infinite impedance to the flow of unidirectional current from the plate source to the line. A choke coil 34 is provided to prevent the flow of 110 amplified current through the plate current source, while permitting the flow of current from said source through the plate circuit and space path within the amplifier.

115 Plate current is supplied to the several 120 vacuum tube devices by the battery 35 and heating current to their filament by a battery 36, through an adjustable resistance 37. The source of plate current is connected to the vacuum tube devices through the respective choke coils associated with them.

125 Selection of the desired side band may be attained solely by the tuned circuit 24-25-26 and 27.

130 In this case, as shown in Fig. 2, wherein

are used the same reference characters, provided with subscripts, as were applied to the same elements in Fig. 1, the output circuit of the modulating tube includes the condenser 21₁ and the inductance 22₁. The condenser 21₁ performs the same functions as the condenser 21 of Fig. 1.

The circuit 24₁—25₁—26₁ and 27₁, associated with the inductance 22₁, is tuned to the side band which is to be transmitted to the line. This circuit, therefore, performs the double function of selecting the desired side band and, by a proper adjustment of the resistance 27₁, equalizing the amplitudes of the current components of carrier and side-band frequencies supplied to the load circuit. In every other respect the circuit arrangement and connections are the same as shown in Fig. 1.

While in the preceding description an oscillator including a space discharge device having a tuned circuit included in its input circuit has been described as a source of carrier current, by way of example, it will be appreciated that an oscillator having a condenser shunting the coupling coils to constitute a tuned circuit, as disclosed in U. S. Patent No. 1,356,763, issued October 26, 1920, to Hartley, or a resonant circuit in the output circuit of the tube, as shown in Fig. 3—C on page 69 of the Proceedings of the Institute of Radio Engineers, vol. 6, No. 2, April, 1918, would be equally effective and may therefore be substituted for the oscillator described above.

Again, while the connection between the output circuit of the modulator and the selective circuit connected to the amplifier is shown as consisting of a coil having a small number of turns, this is done merely with the object of indicating that these circuits should be loosely coupled together; hence, any method of effecting a loose coupling between these circuits may be used.

Finally, it may be stated, that while for the sake of a complete and clear disclosure, elements of a particular type and one use to which this invention may be applied have been shown and described specifically, it is to be understood that this invention is not to be confined to the specific elements illustrated or the use described, but is to be limited only by the scope of the appended claims.

What is claimed is:

1. The method of transmitting signals, which comprises modulating a carrier current by signaling current and equalizing the amplitudes of the current components, of carrier and side-band frequencies transmitted whereby maximum signaling effect may be produced at a receiving station.

2. The method of transmitting signals, which comprises modulating a carrier current of audio frequency by current of ringing frequency and equalizing the amplitudes

of the current components of carrier and side-band frequencies whereby minimum line current will produce a maximum signaling effect at a receiving station.

3. The method of transmitting signals, which comprises modulating a carrier current of audio frequency by current of ringing frequency, selecting one side-band, and changing the current components of carrier and side-band frequencies to equal values for transmission whereby maximum signaling effect may be produced at a receiving station.

4. The method of transmitting signals, which comprises modulating a carrier current of audio frequency by current of ringing frequency, simultaneously selecting one side band and equalizing the current components of carrier and side-band frequencies.

5. In a signal transmitting system, a modulator, means for impressing carrier current and signaling current on said modulator, and means in the outgoing circuit from said modulator for selecting one side-band and for varying the impedance to the flow of current components of carrier and side-band frequencies from the modulator in the inverse ratio of their amplitudes.

6. In a signal transmitting system, a modulator, means for impressing carrier current and signaling current on said modulator, and means in the outgoing circuit from said modulator for changing the amplitudes of the current components of carrier and side-band frequencies from said modulator to equal values.

7. A signaling system comprising a source of carrier current, a source of signaling current, a modulator having its input circuit connected to said sources, and a tuned circuit associated with its output circuit to select one side-band, provided with means to vary the impedance to the flow of current components of carrier and side-band frequencies in the inverse ratio of their amplitudes.

8. A signaling system comprising a source of carrier current, a source of current of ringing frequency, a modulator having its input circuit connected to said sources, a tuned circuit selective of one side-band, associated with the modulator output circuit, adapted to equalize the amplitudes of the current components of carrier and side-band frequencies.

9. A signaling system comprising a source of carrier current of audio frequency, a source of current of ringing frequency, a modulator having its input circuit connected to said sources, a circuit tuned to one side-band associated with the modulator output circuit, and means for changing to equal values the amplitudes of the current components of carrier and side-band frequencies transmitted whereby maximum signaling effect may be produced at a receiving station.

10. The method of transmitting signals over a toll line provided with voice range repeaters, which comprises modulating a carrier current of audio frequency by current of ringing frequency, selecting one side-band, and equalizing the current components of audio and side-band frequencies transmitted whereby minimum line current will produce a maximum signaling effect at a receiving 10 station.

11. A signal transmitting system comprising a toll line including voice range repeaters, means for modulating a carrier current of audio frequency by current of ringing frequency, and means for equalizing the amplitudes of the current components of carrier and side-band frequencies transmitted over said line whereby minimum line current will produce a maximum signaling effect at 20 the receiving station.

12. A signaling system comprising a source of carrier current, a source of signal-

ing current, a modulator having its input circuit connected to said sources, a selecting circuit connected to the modulator output circuit for selecting one side-band, and means included in said selecting circuit to adjust the amplitudes of the transmitted side-band with respect to the amplitude of the transmitted unmodulated carrier current. 25 30

13. A signaling system comprising a source of carrier current, a source of signaling current, a modulator having its input circuit connected to said sources, a tuned circuit connected to the modulator output circuit to select one side-band and means included in said tuned circuit to adjust the amplitudes of the transmitted unmodulated and modulated currents with respect to each other. 35

In witness whereof, I hereunto subscribe my name this 8th day of December, A. D., 1920.

J. WARREN HORTON.
